HOLDER FOR DRINK DISPENSING VESSEL

George R. Thomsen, Kirkwood, Mo.

Application October 3, 1955, Serial No. 38,212

Term of patent 3½ years

(Cl. D2—3)

FIG.3.

FIG.4.

Fig. 1 is a top plan view of a holder for drink dispensing vessel, embodying my new design,

Fig. 2 is a side elevational view of the holder,

Fig. 3 is an elevational view of the pouring end of the holder, and

Fig. 4 is an elevational view of the end opposite to the pouring end of the holder.

I claim:

The ornamental design for a holder for drink dispensing vessel, substantially as shown.
